UNITED STATES PATENT OFFICE.

HOWARD A. THOMPSON, OF WILKINSBURG, PENNSYLVANIA, ASSIGNOR TO THE UNION
SWITCH & SIGNAL COMPANY, OF SWISSVALE, PENNSYLVANIA, A CORPORATION
OF PENNSYLVANIA.

VOLTAGE-REGULATING APPARATUS.

Application filed February 13, 1925. Serial No. 8,918.

My invention relates to voltage regulating apparatus, that is, to apparatus for supplying a substantially constant voltage to an electro-responsive device from a source of alternating current the voltage of which varies.

I will describe one form and arrangement of apparatus embodying my invention, and will then point out the novel features thereof in claims.

The accompanying drawing is a view, partly diagrammatic and partly in perspective, showing one form of apparatus embodying my invention.

Referring to the drawing, the reference characters 1 and 1^a designate the track rails of a stretch of railway track over which the traffic moves in both directions. A track section A—B is separated from the rest of the stretch by means of insulated joints 2—2 interposed in the two track rails.

The section A—B is provided with track-way circuits intended for co-operation with train carried governing means responsive to the presence of alternating current in the track rails. Since such governing apparatus is usually controlled by the trackway currents through the medium of suitable receiving apparatus carried on the train in advance of the forward axle, and since trains proceed in both directions over section A—B, it follows that means must be provided for supplying the track section with alternating current at each end of the section. I accordingly provide the section with two track transformers T' and T², located at the left hand and right hand ends, respectively, of the section and each having a secondary winding 4 constantly connected across the rails at the adjacent end of the section. An impedance 3 is interposed between the secondary 4 of each track transformer and one rail 1^a of the associated section A—B in the usual manner.

The supply of alternating current to the two track transformers T' and T² is controlled by an auxiliary relay S controlled by means forming no part of the present invention and omitted from the drawing for the sake of simplicity. This relay is so controlled that the relay is normally deenergized, but is energized when a train moving from right to left enters section A—B and is retained in the energized condition as long

as the train occupies the section. As shown 55 in the drawing, relay S is de-energized and under these conditions transformer T' is de-energized but transformer T² is energized, its primary winding 5 being connected, over back contact 6—8 of relay S, with terminals 60 J and K of a suitable source of alternating current not shown in the drawing. When relay S is energized, transformer T² is de-energized but transformer T' is then supplied with current from terminals J and K 65 over front contact 6—7 of relay S. It will thus be plain that when section A—B is occupied by a train moving from left to right or is unoccupied, alternating current is supplied to the section from transformer T², but 70 that when the section is occupied by a train moving from right to left the alternating current is supplied to the rails by transformer T'.

Section A—B is further provided with a 75 track relay R arranged to receive energy from the track rails at a point adjacent transformer T'. Due to the impedance of the track rails, and to the leakage through the track ballast, the difference of potential 80 between the rails of the section A—B at point A will be considerably greater when the section is being supplied with alternating current from transformer T' than when transformer T² is supplying the current to 85 the section. In the absence of any preventative means this widely varying difference of potential would be applied to the terminals of the relay and might damage it. This condition is undesirable and I therefore provide 90 a regulating transformer D to maintain substantially constant the voltage applied to the relay irrespective of variations in the difference of potential between rails at point A. This transformer D comprises a continuous 95 magnetizable core 9 having a first leg 11 carrying a primary winding 15 connected across the rails adjacent point A. Opposite to leg 11 is a second leg 10 as designed and proportioned that for normal values of potential 100 difference between rails at point A, that is, when transformer T² is energized, the leg 10 is magnetically saturated. The transformer D also comprises a magnetic leakage member 12 of magnetic material which member forms a shunt around leg 11 of core 9. The member 12 is separated from the core 9 by two air gaps 13 and 13^a and carries a sec-

ondary winding 14. A portion of the flux created by winding 15 threads winding 14 and induces therein an electromotive force. Secondary winding 14 is connected in series 5 with relay R, and the relay and winding 14 are in turn connected across winding 15 in such manner that the voltage induced in winding 14 is opposed to the voltage applied to winding 15 from the track rails.

10 The parts are so proportioned that when section A—B is supplied with alternating current from transformer T², the voltage across relay R is of the proper value for operating relay R and the magnetic flux in core 15 9 is of such value that leg 10 is saturated. Then if the voltage across the rails at point A increases, as by the energization of transformer T', the increased potential difference between the rails at point A causes an increase 20 in the current through winding 15 which results in an increased flux through leg 11. Leg 10 is, however, saturated and so the larger part of the additional flux threads through member 12 thus increasing 25 the voltage induced in winding 14. Since this voltage opposes the voltage supplied from the rails, the result is that the increase in difference of potential effective at the terminals of the relay is less than the actual increase 30 in the difference of potential between rails.

The ratio of turns in windings 15 and 14 is so chosen that a given increase in voltage applied to winding 15 causes an equal 35 increase in the voltage induced in winding 14. With this arrangement it is plain that the voltage applied to the terminals of relay R is substantially constant over a wide range 40 of variation in the potential difference between rails.

The relay R may be used to control apparatus not shown in the drawing, such as a trackway signal, in any desired manner.

I do not in the present case, make any 45 claim for the combination of the transformer D with the track rails and track relay of a railway signaling system, such invention being claimed in my co-pending application filed on the 15th day of August, 1924, 50 Serial No. 732,196, for railway traffic controlling apparatus.

Although I have herein shown and described only one form and arrangement of apparatus embodying my invention, it is understood that various changes and modifications may be made therein within the scope of the appended claims without departing from the spirit and scope of my invention. 55

Having thus described my invention, what I claim is:

1. In combination, a source of alternating current having a variable voltage, an electro-responsive device supplied with current from said source, a continuous magnetizable core having a first leg carrying a primary winding connected in parallel with said device, and having a second leg that is magnetically saturated when the voltage of said source is at normal value, a magnetizable leakage member shunting said first leg, and a secondary winding on said member and connected in series with said device in such manner that the voltage induced in said secondary is opposed to the potential applied 70 to the device from the source. 75

2. In combination, a source of alternating current having a variable voltage, an electro-responsive device supplied with current from said source, a transformer comprising a core having a first leg carrying a primary winding connected in parallel with said device and having a second leg that is magnetically saturated at normal value of the voltage of said source, a magnetic leakage member shunting said first leg, and a secondary winding on said member connected in series with said device. 85

3. Voltage regulating apparatus comprising a magnetizable core carrying a primary winding and having a leg which is saturated at the normal voltage applied to said primary winding, a magnetic leakage member shunting the part of said core which carries the primary winding, and a secondary winding on said leakage member connected with said primary winding but so wound that the voltage induced therein by current in the primary winding opposes the voltage applied to the primary winding. 90 95 100

In testimony whereof I affix my signature.
HOWARD A. THOMPSON.
